MULTIPLIER COUPLING SYSTEM

Philo T. Farnsworth, Springfield Township, Montgomery County, Pa., assignor to Farnsworth Television Incorporated, San Francisco, Calif., a corporation of California

Application March 22, 1937, Serial No. 132,330

14 Claims. (Cl. 250—36)

My invention relates to electron multipliers, and more particularly to a means and method of coupling an external circuit to the multiplier in such a manner that variations in load have 5 a minimum effect on the operation of the multiplier.

Among the objects of my invention are: To provide an electron multiplier and coupling therefor; to provide a means and method of abstracting power from an oscillating electron multiplier with a minimum of oscillation disturbance; to provide a means and method of collecting electrons after electron multiplication; to provide a means of coupling a standard 10 frequency oscillator to a power consuming circuit; and to provide a simple, efficient and stable means and method of abstracting power from an electron multiplier.

My invention possesses numerous other objects and features of advantage, some of which, together with the foregoing, will be set forth in the following description of specific apparatus embodying and utilizing my novel method. It is therefore to be understood that my method is 25 applicable to other apparatus, and that I do not limit myself, in any way, to the apparatus of the present application, as I may adopt various other apparatus embodiments, utilizing the method, within the scope of the appended 30 claims.

Referring to the drawing:

Figure 1 is a longitudinal sectional view through a preferred form of the tube of my invention, together with a diagrammatic circuit 35 for placing the device in operation.

Figure 2 is a cross sectional view, taken as indicated by the line 2—2 in Figure 1.

Figure 3 is an enlarged sectional view of a portion of the device showing an alternative 40 method of coupling the output of a multiplier to a transmission line.

In my prior Patent No. 2,071,516, granted February 23, 1937, entitled "Oscillation generator," I have described a cold cathode electron 45 multiplier capable of self-oscillation. One modification of this device has been shown to be a diode, and in my application, Serial No. 132,327, filed March 22, 1937, entitled Diode oscillator tube construction, I have described several forms 50 which this diode may take, a preferred form being merely a cathode cylinder enclosing an apertured anode, the cylinder having its inner surface sensitized for the generation of secondary electrons at a ratio greater than unity 55 upon electron impact therewith.

By connecting an external resonant circuit between anode and cathode, and by supplying the anode with a source of potential more positive than the cathode, I have been able to cause the device to self-oscillate by causing the oscillation within the cathode chamber of an electron cloud which repeatedly impacts the cathode to generate secondaries. The device will reach an equilibrium value, maintain itself in self-oscillation, and power can be drawn therefrom. 10

In common with other generators, this oscillator is also sensitive to variations in load, and it is desirable, therefore, when the device is being used as a master oscillator or standard frequency oscillator feeding a power consuming circuit which may vary in its demand, to take precautions that the power absorbed shall not interfere with the operation of the oscillator. 15

The present invention deals with a means and 20 method of abstracting power from an electron multiplier, preferably a diode, in such a manner that it will not, to any great extent, interfere with the operation of the multiplier itself.

Broadly as to method, my invention comprises 25 oscillating a cloud of electrons against and away from a cathode capable of generating secondary electrons at a ratio greater than unity upon each impact therewith, collecting a portion of the electrons, segregating another portion of the 30 electrons and directing them away from the oscillating structure, and thereafter collecting them within a unipotential space.

Broadly, as to apparatus, my invention comprises a cathode capable of emitting secondaries 35 at a ratio greater than unity upon electron impact therewith, and an anode so positioned and energized as to cause an oscillation of an electron cloud against and away from the cathode. Self-oscillation is preferably obtained by connecting the anode and cathode with a resonant 40 circuit and energizing the anode to a potential more positive than the cathode, or, putting it another way, in this particular case making the cathode more negative than the anode, as I prefer to work with the anode at ground potential. A portion of the oscillating cloud is collected by the anode; another portion passes through an aperture in the cathode into the interior of a Faraday cylinder, and is there collected. The 45 Faraday cylinder is maintained at a potential higher than either the anode or cathode of the multiplier, and in my preferred form is connected by a resonant circuit to the cathode.

The advantages of such a means and method 50

may be more fully understood by direct reference to the drawing, which shows two preferred structural embodiments of my invention utilizing my improved method.

5 In Figure 1, an envelope 1, which may be a cylinder, is normally closed at one end and has the other end closed by a reentrant stem 2. Carried on the stem 2 by appropriate supports is a cylindrical cathode 4 and an apertured 10 anode 6, which in this case may be formed by winding a fine refractory wire 8 on upright supports 7. I also prefer to have the two electrodes concentrically positioned with respect to each other.

15 At one point in the surface of the cathode I cut a cathode aperture, and partially close it with a screen 9. While the size and shape of this aperture is not important, I prefer to utilize an aperture shaped to match the open end of 20 a tubular collecting electrode 10, the open end being positioned closely adjacent the screen 9 and extending away from the cathode on the outside thereof. I also prefer to position the aperture midway between the open ends of the 25 cathode, as it is here that the maximum concentration of electrons usually occurs. Tubular electrode 10 is positioned in a side arm 11 of the envelope, and is supported by a lead 12 entering the end of the side arm.

30 In order to operate the device, I prefer to connect a multiplier resonant circuit 14 between anode 6 and ground. A radio frequency ground is provided for cathode 4 by the connection of by-pass condenser 15 between cathode 4 and ground. Collecting cylinder 10 is raised to a 35 relatively high positive potential by collecting source 16 in series with a collector resonant circuit 17. Energizing the device as shown, it will be found that the anode 6 is held at a D. C. 40 ground potential, but is connected to the cathode through the resonant circuit 14 and by-pass condenser 15. Cathode 4 is maintained at a fixed negative D. C. potential but with a ground R. F. potential. Thus there will be very little coupling 45 between collecting cylinder 10 and anode 6. Under these conditions the diode combination of cathode 4 and anode 6 becomes a self-oscillator.

I prefer to sensitize the inner surface of cathode 4 so that secondary electrons will be emitted 50 on electron impact therewith at a 1 to 1 ratio when electrons impact at about twenty volts velocity, and if I form the cathode 4 of silver, oxidize its surface, and sensitize the surface with caesium, I find that secondaries can be produced 55 with ratios as large as 10 or 12 to 1 at higher velocities.

Due to the action of the resonant circuit 14, and the fact that anode 6 is at a potential more 60 positive than cathode 4, continuous oscillation of the diode structure takes place as described in my prior applications referred to above, with the electrons repeatedly and cyclically impacting cathode 4 and producing secondaries, some 65 of which are constantly being collected by anode 6 and being used to maintain self-oscillation. However, in the vicinity of the aperture screen 9 some of the electrons approaching the surface of the cathode at this point will, of course, pass 70 through the screen and enter the space enclosed by collecting cylinder 10, and eventually be collected.

I prefer to utilize a tubular collector for several reasons. First, electrons of all velocities 75 will be collected substantially simultaneously, the higher velocity electrons passing through to the

end of the cylinder and the lower electrons being collected by the side walls without going to the end. Furthermore, the cylinder has a distinct focusing action, and as most of the electrons passing through the screen 9 will be of high 5 velocity, they will liberate heat at the area of collection. Inasmuch as the sensitive caesium surface which I prefer to use is readily affected adversely by heat, it is of great advantage to have the hot spot where the majority of electrons are collected, as far away as possible from the cathode. The tubular electrode is an efficient means of collecting all the electrons passing through the screen 9, and at the same time keeps the impact area heated by the high 10 velocity electrons at a distance away from the sensitized cathode surface. 15

As an example of the efficiency of the device, coupled in this manner to an external circuit such as 17, I have found that when 600 volts 20 difference is utilized between the multiplier anode and cathode, and 2000 volts between multiplier anode and collector 10, that anode 6 will, in one embodiment, pick up ten milliamperes of current, whereas the collector will pick up two 25 milliamperes of current. This amount of power may be abstracted with the oscillator with a minimum of disturbance of the amplitude or frequency of the oscillator, and therefore the variations in circuit 17 have little or no effect on 30 the oscillator itself.

It is obvious that circuit 17 may be the power consuming circuit in the device shown in Figure 1. In Figure 3 I have shown a coupling means whereby the power collected by cylinder 10 may 35 be transferred directly into a tubular conductor for use as desired. Here, the lead 12 for the tubular electrode 10 passes, preferably, through the side wall of the envelope 1, leaving the end wall 20 of the side arm 11 clear. Under these 40 conditions a tubular conductor 21 may be slipped on over the side arm outside of the envelope wall, and is capacitatively coupled to the collector 10. In this case collector 10 is fed from source 16 through R. F. choke 22.

The devices I have shown here illustrate, of course, only two particular forms of power consuming circuit. Other structures and other circuits embodying my invention will be apparent to those skilled in the art, and are deemed to 50 fall within the scope of my invention as defined within the appended claims.

The invention, while described as applied to a multiplier diode, is obviously applicable to any electrode where electrons repeatedly and cyclically impact the surface thereof with a velocity sufficient to pass through an aperture therein. 55

I claim:

1. In combination, an electron multiplier comprising an envelope containing a unipotential 60 cathode capable of emitting secondary electrons at a ratio greater than unity upon electron impact therewith, and having an aperture therein, an anode on one side of said cathode, external circuit means for causing electrons to make continuous cyclical impacts with said cathode at a 65 velocity sufficient to produce secondaries and sustain oscillation of said electrons, and a hollow collector on the other side of said cathode having an open end adjacent said aperture to receive electrons passing therethrough.

2. In combination, an electron multiplier comprising an envelope containing a unipotential cathode capable of emitting secondary electrons at a ratio greater than unity upon electron im- 75

5 pact therewith, and having an aperture therein, an anode on one side of said cathode, external circuit means for causing electrons to make continuous cyclical impacts with said cathode at a velocity sufficient to produce secondaries and sustain oscillation of said electrons, and an elongated tubular electrode extending away from said cathode and having an open end adjacent said aperture to receive electrons passing there-
10 through.

10 3. In combination, an electron multiplier comprising an envelope containing a unipotential cathode capable of emitting secondary electrons at a ratio greater than unity upon electron impact therewith, and having an aperture therein, an anode on one side of said cathode, external circuit means for causing electrons to make continuous cyclical impacts with said cathode at a velocity sufficient to produce secondaries and 15 sustain oscillation of said electrons, an elongated tubular electrode extending away from said cathode and having an open end adjacent said aperture to receive electrons passing therethrough, and an external circuit connected from said 20 cathode to said tubular electrode including a 25 source of positive potential for said electrode.

25 4. In combination, an electron multiplier comprising an envelope containing a unipotential cathode capable of emitting secondary electrons 30 at a ratio greater than unity upon electron impact therewith, and having an aperture therein, an anode on one side of said cathode, external circuit means for causing electrons to make continuous cyclical impacts with said cathode at a 35 velocity sufficient to produce secondaries and sustain oscillation of said electrons, an elongated tubular electrode extending away from said cathode and having an open end adjacent said aperture to receive electrons passing therethrough, an 40 external circuit connected from said cathode to said tubular electrode including a source of positive potential for said electrode, and a circuit resonant to the oscillation frequency, connecting said tubular electrode to said cathode.

45 5. In combination, an electron multiplier comprising an envelope containing a unipotential cathode capable of emitting secondary electrons at a ratio greater than unity upon electron impact therewith, and having an aperture therein, an anode on one side of said cathode, external 50 circuit means for causing electrons to make continuous cyclical impacts with said cathode at a velocity sufficient to produce secondaries and sustain oscillation of said electrons, an elongated 55 tubular electrode extending away from said cathode and having an open end adjacent said aperture to receive electrons passing therethrough, an external circuit connected from said cathode to said tubular electrode including a source of positive potential for said electrode, a circuit resonant 60 to the oscillation frequency connecting said tubular electrode to said cathode, and a tubular conductor surrounding said tubular electrode outside of said envelope.

65 6. In combination, an electron multiplier comprising an envelope containing a unipotential cathode capable of emitting secondary electrons at a ratio greater than unity upon electron impact therewith, and having a screened aperture 70 therein, an anode on one side of said cathode, external circuit means for causing electrons to make continuous cyclical impacts with said cathode at a velocity sufficient to produce secondaries and sustain oscillation of said electrons, and a 75 hollow collector on the other side of said cathode greater than unity at each impact therewith.

having an open end adjacent said aperture to receive electrons passing therethrough.

7. In combination, an electron multiplier comprising an envelope containing a unipotential cathode capable of emitting secondary electrons 5 at a ratio greater than unity upon electron impact therewith, and having a screened aperture therein, an anode on one side of said cathode, external circuit means for causing electrons to make continuous cyclical impacts with said cathode at a velocity sufficient to produce secondaries and sustain oscillation of said electrons, and an elongated tubular electrode extending away from said cathode and having an open end adjacent said aperture to receive electrons passing there- 10 through.

15 8. In combination, an electron multiplier comprising an envelope containing a unipotential cathode capable of emitting secondary electrons at a ratio greater than unity upon electron impact therewith, and having a screened aperture therein, an anode on one side of said cathode, external circuit means for causing electrons to make continuous cyclical impacts with said cathode at a velocity sufficient to produce secondaries and 20 sustain oscillation of said electrons, an elongated tubular electrode extending away from said cathode and having an open end adjacent said aperture to receive electrons passing therethrough, and an external circuit connected from said cathode to said tubular electrode including a source of positive potential for said electrode.

25 9. In combination, an electron multiplier comprising an envelope containing a unipotential cathode capable of emitting secondary electrons 30 at a ratio greater than unity upon electron impact therewith, and having a screened aperture therein, an anode on one side of said cathode, external circuit means for causing electrons to make continuous cyclical impacts with said cathode at a velocity sufficient to produce secondaries and sustain oscillation of said electrons, an elongated tubular electrode extending away from said cathode and having an open end adjacent said aperture to receive electrons passing therethrough, an external circuit connected from said cathode to said tubular electrode including a source of positive potential for said electrode, and a circuit resonant to the oscillation frequency, connecting said tubular electrode to said cathode.

35 10. In combination, an electron multiplier comprising an envelope containing a unipotential cathode capable of emitting secondary electrons at a ratio greater than unity upon electron impact therewith, and having a screened aperture therein, an anode on one side of said cathode, external circuit means for causing electrons to make continuous cyclical impacts with said cathode at a velocity sufficient to produce secondaries and sustain oscillation of said electrons, an elongated tubular electrode extending away from said cathode and having an open end adjacent said aperture to receive electrons passing therethrough, an external circuit connected from said cathode to said tubular electrode including a source of positive potential for said electrode, a circuit resonant to the oscillation frequency connecting said tubular electrode to said cathode, and a tubular conductor surrounding said tubular electrode outside of said envelope.

40 11. The method of abstracting power from an electron multiplier, which comprises oscillating a 45 cloud of electrons against and away from a surface to produce secondary emission at a ratio 50 of 50 to 1 at each impact therewith, 55

collecting a portion of said electrons, utilizing the energy of the collected portion to maintain oscillation of said cloud, directing another portion of said electrons away from said surface, and collecting said latter electrons in a unipotential space.

12. The method of abstracting power from an electron multiplier, which comprises oscillating a cloud of electrons against and away from a surface to produce secondary emission at a ratio greater than unity at each impact therewith, collecting a portion of said electrons, utilizing the energy of the collected portion to maintain oscillation of said cloud, directing another portion of said electrons away from said surface, and electrostatically focusing said latter electrons on a spot removed from said surface.

13. The method of abstracting power from an electron multiplier, which comprises oscillating a cloud of electrons against and away from a surface to produce secondary emission at a ratio

greater than unity at each impact therewith, collecting a portion of said electrons, utilizing the energy of the collected portion to maintain oscillation of said cloud, directing another portion of said electrons away from said surface, and collecting all velocity components of said latter electrons at substantially the same time.

14. The method of abstracting power from an electron multiplier, which comprises oscillating a cloud of electrons against and away from a surface to produce secondary emission at a ratio greater than unity at each impact therewith, collecting a portion of said electrons, utilizing the energy of the collected portion to maintain oscillation of said cloud, directing another portion of said electrons away from said surface, collecting all velocity components of said latter electrons at substantially the same time, and utilizing the energy of said latter electrons in a work circuit.

PHILO T. FARNSWORTH.
